UNITED STATES PATENT OFFICE.

NELSON WHITE, OF PORTLAND, OREGON, ASSIGNOR, BY MESNE ASSIGNMENTS, TO
INTERNATIONAL MONEY MACHINE COMPANY, OF TERRE HAUTE, INDIANA, A
CORPORATION OF INDIANA.

COIN-DELIVERY MACHINE.

1,244,812.

Specification of Letters Patent. Patented Oct. 30, 1917.

Application filed May 12, 1914. Serial No. 838,065.

To all whom it may concern:

Be it known that I, NELSON WHITE, a citizen of the United States, residing at Portland, in the county of Multnomah and 5 State of Oregon, have invented certain new and useful Improvements in Coin-Delivery Machines, of which the following is a specification.

The present invention appertains to the 10 art of money handling machines, and consists of a machine designed particularly for facilitating the delivery of coins of different denominations for making change.

The introduction in many cities of "pay 15 as you enter cars," and motor-busses operated by motermen without conductors, has given rise to a considerable need for a compact simple machine of the type above referred to and it is the object of this invention 20 to provide such a machine, of a construction comparatively cheap to manufacture, occupying a small amount of space, and susceptible of very quick operation to meet the desired requirements.

25 A further object of the invention has been to produce a coin delivery machine which comprises suitable coin receptacles housed by a casing which is a movable section normally positioned so as to prevent unauthorized access to the money receptacles, but 30 which may be readily moved upon releasing certain locking devices to expose the receptacles for the purpose of replenishing the same, or the like.

35 Still another object of the invention has been to devise a special key mechanism for causing money delivering transactions of the machine, peculiar locking means being associated with the keys of said mechanism 40 whereby upon turning a pocket key which goes with the machine the operator is able to lock the machine from operation as is necessary when the machine is not under his direct supervision. A unique feature of the

45 invention resides in the fact that the said pocket key which may be removed entirely from the machine controls also certain locking mechanism for the movable section of the casing which houses the coin receptacles 50 so that by the operation of said pocket key it is possible to release the locking mechanism of the keys which control the ejection of coins, and at the same time, unlock said section so that whenever necessary the

operator may have access to the coin receptacles. On reverse operation of said key the ejection controlling keys and the movable casing section may be locked from movement in the manner hereinbefore suggested. 55

In addition to the foregoing, the invention includes a special form of coin delivery chute and closure or gate for the latter, capable of being moved back and forth to open and close the same, and of being supported in an abnormal open position at the will of the operator. 60 65

The features of invention above referred to, together with their detail features residing in the special controlling and ejecting mechanisms employed will be fully understood upon reference to the following description and the accompanying drawings, in which—

Figure 1 is a perspective view of a coin delivery machine embodying the invention. 75

Fig. 2 is a vertical sectional view of the same taken about on the line 2—2 of Fig. 3, the casing parts being omitted.

Fig. 3 is a top plan view of the internal mechanism of the machine, the casing not illustrated. 80

Fig. 4 is a rear view of the same.

Fig. 5 is a sectional view taken about on the line 5—5 of Fig. 2. 85

Fig. 6 is an end view of the frame and associated parts, casing omitted, bringing out clearly the operative position of the pocket key and the latches employed to lock the casing section for the coin receptacles. 90

Fig. 7 is an end view of the machine illustrating the movable casing section thrown downward to afford access to the coin receptacles, dotted lines bringing out more clearly the key locking means. 95

Fig. 8 is a rear view of the closure for the coin chute, parts arranged in closed positions.

Fig. 9 is a view similar to Fig. 8 but showing the closure adjusted so as to remain in an open position. 100

Fig. 10 is a fragmentary detail of the full stroke mechanism.

In the drawings A denotes the casing of the machine which may be said to comprise 105 a main body portion that houses the frame of the machine and the internal mechanism, together with a movable section or casing

member B situated at the front of the machine so as to practically entirely house the coin receptacles. It will be understood that the casing of the machine may be of any suitable ornamental appearance desired, this being immaterial to the mechanical features of the machine. The coin chute C is located at the front lower portion of the casing member B at a point beneath the coin receptacles D, suitable rods 1 being used to attach the chute C to lugs 2 depending from the base 3 of the frame 4. There is a hinged or pivotal connection 5 between the upper portion of the chute and the lower foremost portion of the casing portion or section B, this section being sustained by a pintle rod passing through loops on the respective parts B and C. The provision of the connection 5 permits of pulling the casing member B upward and downward so that it may occupy the position shown in Fig. 7 and afford complete access to the various receptacles D. At its uppermost portion the casing member B is provided with coin slots 6 of varying sizes to accommodate the entering of coins of different denominations ranging in the present machine from five cents up to one dollar. Apertures may be provided in the front portions of the parts B and C for ornamental purposes, the apertures in the member B also permitting the operator to view the coin receptacles and thus to ascertain when the supply of coins therein is getting low.

As shown in Figs. 2 to 6 inclusive, the frame 4 of the machine consists of vertical end or frame members 4' which are connected together by tie rods 7 as well as by certain shafts which extend longitudinally of the frame and on which certain parts of the mechanism are mounted. Thus it is that the manipulative keys 8 that control ejection of the coins are pivoted at their rear-most ends upon a rod 7 and maintained in predetermined positions in relation to one another by spacers 9 carried by said rod. The keys 8 have at their rear ends yoke portions 10, each of which is connected by a spring 11 with a plate 12 secured to the front plate 13 of the frame 4 and in advance of which front plate the coin holders or receptacles D are mounted. In addition to having a suitable finger piece 8' marked with indicia denoting the denomination of coin controlled by said key, each key has an arm 14 inclining forward from a side of its yoke portion 10, said arm adapted to cooperate with one of rocker members 15, 15', and 15'', all of which rocker members are mounted laterally on one of the rods 7. The rocker members are peculiarly constructed, each of said members being associated with an ejector 16 and being composed of two plates in vertical, parallel relation connected intermediate their ends by an integral bridge

piece 17 to which is attached one end of a spring 18, the opposite end of which is secured to a yoke 19 at the rear end of each ejector 16. The plates of each rocker member 15 have connecting cross pins at their upper ends 20 and connecting pivot pins 21 at their lower ends, the pins 21 passing through the parts of the member and sides of the yoke 19 of the adjacent ejector 16. In this way each rocker member 15 is pivotally supported on the rod 7 and pivotally connected at its lower end with a certain one of the ejectors 16 and the arm 14 of the co-operating key 8 is adapted to engage the upper pin 20 of the rocker member 15 so that as the key 8 is depressed rocking arm 14 is moved downward and rocking movement is imparted to the member 15 carrying its lower end outward toward the front of the machine and thus imparting oscillatory movement to the ejector 16. At this point it may be noted that each ejector 16 has a coin engaging projection 22 and a pivoted coin supporting finger 23 located at the outer end of the ejector and guided in its movement by a notched bearing formed in the rear wall of the chute C. The lower edge of each finger 23 is formed with an incline 23' that permits the finger to gradually move downward as the coin is ejected thereby removing the finger from a position supporting the coin from beneath and permitting the latter to gravitate into the chute as soon as properly freed from the receptacle D.

Referring particularly to Figs. 2, 3, and 4 it will be observed that the rod 7 which forms the pivotal axis for the rocker members 15, 15', and 15'' has rocker arms 24 and 24' mounted thereon at its opposite ends. These arms 24 and 24' are angle shaped, (see Figs. 2 and 6) the upper portions of the arms being connected by a rod 25 on which is mounted a rotatable sleeve 26, parts 25 and 26 being just above extensions 27 that project forward from the rocker members 15, 15' and 15''. The rocker arm 24 is pivotally connected at its lower end with one of the five-cent ejectors of the machine which ejector is like all of the rest of the ejectors except that it is not associated with a rocker member such as those designated 15, 15' and 15''. A spring 18' connects the ejector 16 attached to the arm 24 with a projection 28 on said arm 24 and said spring tends to raise the ejector resiliently against a guide member 29 on the plate 13 and above a suitable opening in this plate through which the ejector operates.

The right hand plate of all the rocker members 15, and 15'', is formed at its lower terminal with a lateral foot piece 30. The foot piece 30 of each rocker member 15 is capable of engaging a short projection 125 180

extending downward from the left hand plate of the rocker member 15 next on the right as seen in Fig. 4. The object of this arrangement and construction of parts will now be made clear.

There are seven coin receptacles in all in the machine illustrated, two for nickles, two for dimes, one for twenty-five cent pieces, one for fifty-cent pieces, and one for silver dollars. A depression of the ten-cent key 8 causes its arm 14 to engage an elongated pin 32 carried by the upper end of the rocker member 15", thereby tilting said rocker member on its axis 7 and causing the extensions 27 to engage the sleeve 26 and impart rocking movement to arms 24 and 24'. Since a five-cent ejector is connected to the arm 24 and a corresponding five-cent ejector connected to the lower end of the rocker member 15", two nickels will be ejected from the machine in depressing the ten-cent key. On depressing any key 8 it is contemplated that the arms 24 and 24' shall be rocked so as to eject a nickel along with other coins that make up the valuation of the amount denoted on the finger piece of such key.

Supposing now the twenty-five cent key 8 is depressed, its arm 14, by engaging the pin 29 of the associated rocker member 15, causes tilting of said rocker member which is the third one from the right hand end of the machine viewed in Fig. 4. During this operation of said member 15 by the twenty-five cent key, extensions 27 of the member 15 engage with sleeve 26 and cause tilting of the rocker arms 24 and 24' so as to insure the delivery of a nickel from the machine. Likewise the foot 30 of the member 15 connected with the fourth ejector from the right of the machine engages the projection 31 of the rocker member 15" so that it will be evident that a depression of the twenty-five cent key will cause simultaneous movement of the arm 24 and its ejector 16, the rocker member 15" and its ejector 16, and the rocker member 15 just to the left of the rocker member 15" in Fig. 4. In this way two ten cent pieces and a five cent piece are delivered from the machine.

The foregoing is the idea of each transaction of the machine. The only time the rocker member 15" is operated is when the ten-cent or extreme right key in Fig. 4 is depressed. The grouping of the keys 8 and the manner in which they are connected to operate the ejectors is such that the higher the denomination of the key, the larger is the number of rocker members 15 and 15" that are moved simultaneously with the rocker arm 24. Furthermore, the projection 22 of the ejector 16 that governs the coin receptacle D for silver dollars is sufficiently high that four silver dollars will be ejected every time the ejector 16 of said receptacle is operated by the depression of the five

dollar key. In other words in the operation of the machine the keys 8 upon depression actuate one or more of the ejectors 16 which are connected with the rocker members 15 and 15", together with the ejector 16 which is attached to the rocker arm 24. The grouping of the rocker member 15 and 15" is determined empirically so that if it is desired to render the machine capable of delivering money in larger amounts than can be ejected from the machine described, it is only necessary to add keys 8, ejectors and coacting rocker members 15 with associated detail parts.

The key locking mechanism is seen best on reference to Figs. 2, 5 and 7, wherein it will be observed that the plate 12 with which the springs 11 are connected is bent outwardly at its upper end to form a sort of trough or guide 12^a in which are mounted in alinement a plurality of short slideable locking bolts 33, the ends of which are tapered as seen in Fig. 5 excepting in respect to the outermost bolt, the end of which is reduced as at 33'. The bolts 33 are permitted to operate in a limited amount of space, and as viewed in Fig. 5 these bolts have been forced inwardly in the guide 12^a to the limit of their movement and are maintained in such position by a locking plate 34 seen in dotted lines in Fig. 7. When so arranged the bolts 33 have their tapered ends held rigid beneath the shanks of the keys 8 rendering it impossible to press said keys downward so long as the members 33 have no freedom of movement in the guide 12^a. It will be obvious, however, that if the plate 34 is moved into a position in which it clears the end 33' of the outermost bolt 33, should a key 8 be depressed, it will strike the adjacent tapered end of its associated bolt and slide said bolt outward so that the latter does not interfere with the depression of the key and thereby permits a transaction of the machine to be performed. The problem of locking the keys 8, therefore, has been merely to utilize the plate 34 or its equivalent, pivotally mounted on the inner side of one end wall of the casing A so that it may be thrown from a position engaging the part 33' of the outermost bolt into a position in which it is not opposite said part and therefore permits the slight longitudinal movement of the bolts 33 when impinged by the keys 8 in the manner above described.

To operate the locking plate 34 it is contemplated to use a pocket key 35 insertible in a boss 36 on the casing A until projections on the key engage the plate 34 interlockingly and enable the latter to be turned slightly by the key. When the key 35 is turned to the right so as to move the plate 34 opposite the member 33' thereby locking the bolts 33 and rendering the keys 8 inoperative, said plate 34 simultaneously im-

pings at its lower end with a catch 37 mounted on a shaft 38 supported in bearings in the frame 4, said shaft extending all the way through the frame and carrying a catch 37' on the end opposite that having the catch 37. The catches 37 and 37' have hook shaped noses to engage with lugs or pins 39 which project inward from the casing member B. When the bolts 33 are maintained locked by the locking plate 34, the catches 37 and 37' will likewise have been permitted to move by their springs 40 into positions in which they engage the lugs 39 and prevent casing member B from being pulled outward into open positions permitting access to the coin receptacles D. A reversal of the movement of the key 35, however, to release the bolts 33, causes the plate 34 to impinge the upper edges of the catch 37 thereby tilting said catch, its shaft 38, and the other catch 37' into positions disengaged from the lugs 39 and thereby releasing the casing member B which may be opened. It is contemplated that the key 35 shall not be displaceable from the boss 36 except when the keys 8 and casing member B are locked in the manner described.

The rocker arm 24' has been described as being carried by the pivot rod 7 which supports the rocker members 15, 15' and 15''. The rocker arm 24'' forms a part of a full stroke mechanism for the machine in that it carries a full stroke sector 41 with which a full stroke pawl 42 coacts, the latter being influenced by a spring 43 attached thereto. As a key is depressed the arm 24' moves forward with the sector 41 and the pawl 42 so engages the teeth of said sector as to prevent restoring movement of the key until a full depression of the same is performed whereupon the spring 43 tilts the pawl 42 downward so that it rides over the teeth of sector 41 during the return movement of said sector and normalizing action of the keys and associated parts.

As seen in Figs. 8 and 9 the discharge opening of the chute C is normally closed by the closure of gate 44 having the handle 45. A hanger 46 supports the closure 44 and is pivoted to the rear side of the chute C at 47, being also formed with an arc slot 48 from which leads an offset or recess 49. A crank 50 is pivoted to the chute C and has a crank pin 51 operating in the slot 48, recess 49 and spring 52 holding the crank in a predetermined position and being connected with the hanger and the pin 51. When the parts are arranged as in Fig. 8 the pin 51 is seated in a notch at the lower edge of slot 48, a pressure on the handle 45 will readily cause the closure to swing open in either direction the pin 51 riding in the slot 48. Should it be desired to maintain the closure 44 in an open position the operator throws the crank 50 into the posi-

tion shown in Fig. 9 and through the action of the spring 52 on the pin the closure is maintained in such position.

It will be understood that considerable variation may be made in the details of construction of this money delivery machine in so far as the size of the same is concerned, or the general grouping of the mechanism by which an enlargement of the machine for increased capacity may be effected. Furthermore, the term "keys" used in connection with the parts 8 are to be understood as contemplating manipulative devices generally and the term "key" as applied to the pocket key 35, to an operating member of an equivalent nature. The lock plate 34 is limited in its rotative movement by a pin 34^a which enters a slot 34^b of said plate and details of this sort may be employed in the actual embodiment of the invention for practical purposes.

The arrangement and connection of the bolts 33 is such that on the depression of any one of the keys 8 the bolts 33 will be actuated so as to lock those keys which have not been depressed. Under such conditions it is impracticable for more than one key 8 to be depressed at a time as there is only sufficient clearance movement for the bolts to permit of depression of a single key and this is not permitted, of course, when the member 34 is turned to lock the machine from operation.

The fingers 23 fill up the ejector slots at the bottom of the coin holders D and prevent accidental lodging of coins in said slots when the holders are filled. The upturned lip at the outer end of each finger 23 serves to retain the bottom coin of the stack in each holder.

Having thus described the invention, what is claimed as new is:

1. In a coin delivery machine, the combination of coin holders, ejectors therefor, keys for operating the ejectors, a pivot supporting the keys, each key being formed with a downwardly extending arm, a rocker member intermediate each key and an associated ejector, a pivotal support carrying the rocker members and disposed intermediate the ends of the latter, each rocker member consisting of spaced plates and a connecting bridge member between said plates, a pin carried by the upper ends of said plates and engageable by the downwardly projecting arm of the key, and a pivotal connecting member carried by the lower ends of said plates and forming a connection between the rocker member and the associated ejector therefor.

2. In a machine of the type described, the combination of coin holders, ejectors therefor, a supporting frame on which said parts are mounted, a plurality of rocker members pivoted between their ends on said frame,

- connections intermediate said rocker members and certain of the ejectors, a rocker arm co-axially mounted in relation to the said rocker members and connected with 5 one of the ejectors and provided with a forward extension, manipulative keys formed with arms adapted to operate the rocker members and the rocker arm above mentioned, projections extending from the 10 rocker members, and a member connected with the rocker arm and disposed in the path of movement of said projections whereby on the operation of each rocker member the rocker arm and its ejector will be actuated, the relation of the last mentioned member and the said projections being such that the rocker arm may be operated by its key independently of the rocker members associated therewith.
- 15 3. In a coin delivery machine, the combination of coin holders, ejectors associated therewith, a rocking arm connected with one of said ejectors, operating members directly connected with the other ejectors, keys 20 directly coacting with the last-mentioned operating members to control the operation of the ejectors, and means intermediate the rocking arm and said operating members whereby on depression of any key the rocking arm and its connected ejector will be operated with a predetermined one or more of the operating members and their associated ejectors, the last-named means comprising an extension projecting from each 25 operating member, and a member in the path of all of said extensions connected with the rocking arm.
- 25 4. In a money handling machine, the combination of money receptacles, money dis- 30 charging mechanism associated therewith, manipulative keys controlling the operation of said discharging mechanism, a casing member movable to afford access to the money receptacles, and means common to 35 said keys and the casing member for locking the keys inoperative and locking the casing preventing access to the money recep- 40 tacles.
- 40 5. In a money handling machine, the combination of money receptacles, money dis- 45 charging mechanism associated therewith, manipulative keys controlling the operation of said discharging mechanism, a casing member movable to afford access to the 50 money receptacles, and means for simulta- 55 neously locking the keys and casing member from movement.
- 55 6. In a money handling machine, the combination of money receptacles, discharging mechanism associated with said receptacles, manipulative keys controlling said discharging mechanism, a locking bolt associated with each key, a device to simultaneously throw the locking bolts of the several keys into locking positions preventing operation of said keys, a casing member adapted to house the money receptacles and prevent access thereto, and a catch operable by the aforesaid device and controlling locking and releasing of said casing member.
- 60 7. In a money handling machine, the combination of money receptacles, discharging mechanism associated with said receptacles, manipulative keys controlling said dis- 65 charging mechanism, a locking bolt associated with each key, a device to simultaneously throw the locking bolts of the several keys into locking positions preventing operation of said keys, a casing member adapted to house the money receptacles and prevent 70 access to the same, means movably supporting said casing member, catches normally coacting with opposite ends of the casing member, and a shaft connecting said catches together for simultaneous movement, one of 75 the catches being engageable by the above mentioned device so that the latter may cause a locking or releasing movement of the catches.
- 80 8. In a money handling machine, the combination of money receptacles, discharging mechanism associated therewith, a discharge chute adapted to receive money from the receptacles in a discharging operation, a closure for said chute, a hanger pivotally 85 supporting said closure, a crank carried by the chute and having a crank pin, the hanger having a slot in which the said pin operates, and a spring connected with the crank pin and acting on the crank to return the 90 closure to a closed position after movement of the same, said crank being movable into a position to maintain the closure open.
- 90 In testimony whereof I have affixed my signature in presence of two witnesses.
